FRANCIS A. STAFFORD, OF FULTON, NEW YORK, ASSIGNOR TO THE HUNTER ARMS COMPANY, INC., OF FULTON, NEW YORK, A CORPORATION OF NEW YORK.

FIRING MECHANISM FOR FIREARMS.

1,354,701.

Specification of Letters Patent.

Patented Oct. 5, 1920.

Application filed April 27, 1917. Serial No. 164,859.

To all whom it may concern:

Be it known that I, FRANCIS A. STAFFORD, a citizen of the United States, and a resident of Fulton, in the county of Oswego 5 and State of New York, have invented a certain new and useful Firing Mechanism for Firearms, of which the following is a specification.

This invention has for its object a particularly simple and efficient firing mechanism for firearms which consists in a minimum number of parts, and the invention consists in the novel features and in the combinations and constructions hereinafter 10 set forth and claimed.

In describing this invention, reference is had to the accompanying drawings in which like characters designate corresponding parts in all the views.

20. Figure 1 is a side elevation of a trigger plate and contiguous parts of a firing mechanism embodying my invention.

Fig. 2 is a plan of the trigger plate and parts carried thereby.

25. Fig. 3 is a longitudinal sectional view of parts seen in Fig. 1.

Fig. 4 is a plan view of the trigger and sear spring.

This firing mechanism in addition to the 30 hammer, main spring, firing pin and other parts, comprises a sear and a trigger, both of which are preferably carried by the trigger plate, and spring means acting to hold the trigger and sear in engagement to take 35 up any looseness and also to resist movement of the sear by the trigger.

1 designates the trigger plate which has a lug 2 rising therefrom, the plate being secured to the frame 3, of the gun in any well 40 known manner. As here shown, the trigger plate is provided with an enlargement 4 at its rear end through which passes a screw 5 which threads at its upper end into the tang 6. The lug 2 is also formed with a 45 threaded passage opening through its upper end into which turns a screw 7 which passes through said tang 6. 8 is the trigger guard which interlocks at 9 at its front end in a socket in the trigger plate. The trigger guard is secured at its rear end to the stock 50 in the usual manner as by screws passing through holes 10 in the rearward extension 11 of the trigger guard.

12 designates the sear which is here shown

as pivoted between its ends at 13 to one side 55 of the lug 2, it being usually located in the recess 14 in the side of said lug. The front arm of the sear is provided with a laterally extending portion or blade 15 which engages at its end with the notch 16 in the 60 hammer 17. The rear arm of the sear is formed with a laterally extending portion or shoulder 18 overlying the upper edge of the trigger 19. This trigger 19 extends upwardly through a slot in the trigger plate 65 and in the lug 2, and is pivoted to the lug at 20 at a point in the rear and above the pivot of the sear.

The spring means for preventing looseness between the sear and the trigger and 70 for resisting movement of the sear by the trigger, acts to press the trigger upwardly against the shoulder 18 of the sear, and to press the front arm of the sear upwardly.

This spring means comprises a flat bow 75 spring 21 secured intermediate of its ends at 22 to the trigger plate, the spring extending alongside the lug 2 under the sear and pressing upwardly at its front end against the lower side of the front arm of the sear 80 12, and having a lateral extension 23 at its rear end extending into a transverse slot 24, in the plate of the trigger, the spring pressing upwardly against the upper side of the slot 24 and normally tending to hold 85 the edge of the blade of the trigger against the shoulder 18 of the sear.

In operation, very little movement of the sear 12 releases its blade end 15 from the notch 16 of the hammer, and when the hammer is cocked any looseness between the trigger and the rear arm of the sear is taken up by the rear portion 23 of the spring 21. 90

This construction of firing mechanism is particularly advantageous in that the sear 95 is mounted upon the removable trigger plate, and owing to the arrangement of the sear and its spring one spring can be used to perform two functions.

What I claim is:

1. A firing mechanism for firearms comprising a frame, a detachable trigger plate, fixed relatively to the frame, a trigger pivoted to the trigger plate, a sear carried by the trigger plate, and a spring interposed 105 between the sear and the trigger plate and bearing at one end against the sear and at its opposite end on the trigger to hold the

trigger engaged with the sear and resist movement of the sear by the trigger, substantially as and for the purpose described.

2. A firing mechanism for firearms comprising a trigger plate, a trigger pivoted to the trigger plate, a sear pivoted between its ends to the trigger plate, the trigger being located to the rear of the pivot of the sear, and a bow spring having its intermediate 10 part pressing on the trigger plate, its front

arm pressing upwardly on the sear and its rear arm pressing upwardly on the trigger to hold the same against the sear, substantially as and for the purpose specified.

In testimony whereof, I have hereunto 15 signed my name, at Fulton, in the county of Oswego, and State of New York, this 21st day of April, 1917.

FRANCIS A. STAFFORD.
